UNITED STATES PATENT OFFICE.

DAVID C. KLAUSMEYER, OF CINCINNATI, OHIO, ASSIGNOR TO THE CINCINNATI BICK-FORD TOOL COMPANY, OF CINCINNATI, OHIO, A CORPORATION OF OHIO.

SAFETY MANUAL FEED FOR DRILLS.

Application filed July 5, 1923. Serial No. 649,684.

To all whom it may concern:

Be it known that I, DAVID C. KLAUSMEYER, a citizen of the United States, and residing at Cincinnati, in the county of Hamilton and State of Ohio, have invented a new and Improved Safety Manual Feed for Drills, of which the following specification is a full disclosure.

This invention relates to machine tool constructions and more particularly to mechanism for controlling the advance of the tool into the work in power drills.

In machines of this character there is usually provided two trains of mechanism for effecting the relative movement between the work and the tool. One of these trains is manually-driven and the other is power-driven and includes means for determining the rate of feed at which the drill enters the work. Until recently, these two trains of mechanism have been so connected together that the manual drive was in motion during the time the power was operating the mechanism and inasmuch as the hand-wheel for effecting the manual-drive is necessarily exposed, and actuated by the power-drive at speeds ranging from 300 to 500 R. P. M., it was a constant source of danger to the operator.

Recently, however, certain constructions have been designed in which the manual drive is necessarily thrown out of action before the power-drive can be set in action, but in order to attain this result in a practical way, difficulty was experienced in doing so without avoiding certain highly desirable features, particularly the use of sliding sets of speed changing gears for coupling the power shaft with the spindle feeding shaft, or without resorting to a less efficient construction.

It is, therefore, the object of this invention to provide, in a machine of this character, an improved construction selectively permitting either a manual or a power-drive and in which the manual drive will be stationary when the power-drive is active; and to do so in such a manner as to still retain other highly desirable features of construction.

A further object of the invention is to so coordinate the manual and power drives that a single controlling element is capable of effecting all of the adjustments required in changing from one drive to the other, and

which also disconnects the hand drive when the power drive is put into action.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:—

Fig. 1 is a more or less diagrammatic sectional development of a portion of a drilling machine embodying the present invention. Fig. 2 is detail views of certain gear-shift devices later to be referred to. Fig. 3 is a detail sectional view taken on the line 3—3 of Fig. 1 showing, in elevation, the manually-controlled gear-shifting device. Fig. 4 is a detail plan of certain of the elements of this construction, showing particularly the means for disconnecting the manually-controlled feed-wheel from its shaft, and Fig. 5 is a diagrammatic view showing more clearly the connections for shifting the various sets of speed-changing gears.

Referring more particularly to the drawings, the invention is shown in its preferred form in a power-drill including a casing or frame 17 within which is journaled a suitable power-shaft 13 connected (by means of bevel gears 14 and 14^a) to rotate a shaft 15 also journaled in the frame 17. Within the frame 17 is also journaled a spindle feed-shaft 20 upon which is secured a worm-wheel indicated in part at 31. This feed-shaft and worm-wheel are both common to machines of this character and therefore further illustration and description is deemed unnecessary. The worm-wheel 31, as in earlier machines, meshes with a worm 28 secured upon a shaft 18 non-translatably journaled in the frame 17, which shaft may be driven either manually by a hand-wheel 39 or at varying speeds from the power-shaft by mechanism now to be described.

Upon the shaft 15 is splined a gear-unit 20 comprising three integrally formed gear-members 1, 3 and 5 of varying diameters. This gear-unit is adapted to be translated,

2
by mechanism later to be referred to, to bring the gears 1, 3 and 5 into mesh with gears 2, 4 and 6, respectively, formed on a second gear-unit C journaled on bushings 5 surrounding a shaft 12 secured, parallel with the shaft 15, in the frame 17. The gear-unit C is also provided with a gear 8. The gears 6 and 8 are adapted to mesh with gears 7 and 9 formed in a third gear-unit 10 B splined to the shaft 18 and adapted to be translated thereon by mechanism later to be referred to. Thus it will be observed that, with power applied to the shaft 13, by adjusting the gear-units A and B with respect 15 to the unit C, any one of six predetermined speeds may be transmitted to the worm-wheel 31 and its attached spindle feed-shaft.

The manually-controlled feeding-device comprises the hand-wheel 39 having an integrally formed hub 36 within which is fixedly secured, by means of a key 11, a sleeve 34 formed at one end with clutch teeth 33 designed to engage like clutch teeth 35 formed on a second sleeve 48 keyed to the 20 shaft 18. The clutch teeth 33 and 35 are normally urged into engagement by a coil-spring 10 interposed between the sleeve 34 and the head 38 of a cap screw threaded, as at 37, into the reduced end 48^a of the shaft 25 18. Sufficient clearance is provided between the head 38 and the sleeve 34 to permit the sleeve to be moved lengthwise of the shaft 18 sufficiently to disengage the clutch teeth 33 and 35.

30 The mechanism for shifting the gear-units A and B relatively to the unit C comprises a yoke 49 journaled at 50 to a sleeve X loosely fitted upon a tubular support 51 secured at one end in the frame 17. The 35 yoke is provided at one side with a handle 52 and at its other side with an extension 53 terminating in a head 54 adapted to fit within a segmental slot 55 formed in a head 56 fixed to one end of a slide rod 57 provided 40 at its opposite end with a fork 58 adapted to embrace an annular rib 59 on the gear unit A.

The sleeve X is capable of oscillatory movement about the axis of the shaft 18 and 45 is provided in its outer surface with a cam groove 25 within which tracks a roller 24 secured to one end of a second slide-rod 23 having at its opposite end a fork 61 embracing an annular rib 62 on the gear-unit B.

50 From an inspection of Fig. 5 it will be apparent that, by shifting the handle 52 (about its pivot 50 from the position *a* in which gears 3 and 4 are in mesh) to the position *b*, the gears 5 and 6 will be engaged 55 and, by shifting it to the position *c*, the gears 1 and 2 will be brought into mesh.

To complete the connection between the power-shaft 13 and the worm-wheel 31, it is necessary to connect the gear-units B and C. 60

65 This is effected by moving the handle 52 in

a plane transverse to the plane in which it moved to couple the units A and C. This movement causes a partial rotation of the sleeve X about the shaft 18. Thus, if the handle 52 is shifted from its neutral position *d* (shown in Fig. 3) to the position *a*, the sleeve X will be rotated in the direction shown by the arrow *y* and the cam groove 25 will force the roller 24 to the right, as shown by dotted lines in Fig. 4 to cause the gears 6 and 9 to engage. Likewise, a movement of the handle to the position *f* will shift the roller to the left and couple the gears 7 and 8.

To effect the disengagement of the hand-wheel 39 from the shaft 18 (when the lever 52 is adjusted to couple the automatic feed) the sleeve X is formed with a V-shaped notch in one edge. This notch provides cam-faces *g* and *h* which, on the rotation of the sleeve in either direction act upon a tooth Z formed integral with a clutch-disengaging ring 42, splined upon the tubular-support 51 intermediate the sleeve X and the hub 36 of the hand-wheel 39 and forces the hand-wheel outwardly; thus disengaging the clutch teeth 33 and 35. The sleeve is also formed with two detent notches *i* and *j* which prevent accidental shifting of the parts.

55 It will thus be seen that a single hand-lever can be used to adjust several gear-units to produce a plurality of power-drives at different rates, and a single hand-wheel can be resorted to for the purpose of feeding the drill manually; the respective mechanisms being in action only one at a time.

60 Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects 65 of this invention, and, therefore, such adaptations should be, and are intended to be, comprehended within the meaning and range 70 of equivalency of the following claims.

75 Having thus revealed this invention, I claim as new and desire to secure the following combinations and elements, or equivalents thereof, by Letters Patent of the United States:—

1. A drilling machine combining a spindle feed-shaft; automatic means for actuating said shaft including a power shaft, a third shaft, a driving connection between said third shaft and said spindle feed-shaft, and a plurality of relatively shiftable gear-units 80 operatively connecting said power-shaft and said third shaft; manual means for rotating said third shaft to actuate said spindle feed-shaft; and a single feed-controlling element 85 operatively connected with two of said gear- 90 units.

units and movable in one plane to shift one of said gear-units and movable in another plane to shift the other of said gear units to establish a driving connection between said power-shaft and said spindle feed-shaft, and simultaneously therewith to render said manual means inoperative.

2. A drilling machine combining a spindle feed-shaft; automatic means for actuating said shaft at any one of a plurality of speeds including a power-shaft, a third shaft, a plurality of gear-units operatively connecting said power shaft with said third shaft, a driving connection between said third shaft and said spindle feed shaft; manual means for actuating said spindle feed-shaft; a single feed-controlling element movable in one direction to shift one of said gear-units and in another direction to shift another of said gear-units; and means actuated by one of said movements for rendering said manual feeding-actuating means ineffective.

3. A drilling machine combining a spindle feed-shaft; manual means for actuating said shaft; automatic means for actuating said shaft including a power-shaft, a third shaft, a plurality of relatively shiftable gear-units for operatively connecting said power shaft with said third shaft, a driving connection between said third shaft and said spindle feed-shaft; a feed-controlling element constructed and arranged to be moved, first in one plane to shift one of said gear-units and simultaneously therewith to disconnect said manual means, and second in a plane transverse to said first-mentioned plane to shift another of said gear-units to effect a driving connection between said power shaft and said spindle feed shaft.

4. A feeding mechanism for drilling machines combining a frame; a power shaft; a first shaft journaled in said frame and operatively connected with said power shaft; a second and a third shaft supported in said frame parallel with said first shaft; a spindle feed-shaft; a driving connection between said third shaft and said feed-shaft; a plurality of relatively shiftable gear-units operatively connecting said first, second and third shafts, and means for selectively meshing the gears of said gear-units to effect a predetermined speed in said feed-shaft; said means comprising a sleeve rotatably journaled coaxially with said third shaft and providing a cam; an operative connection between said cam and one of said gear-units; a feed-controlling element pivoted to said sleeve and affording means for rotating it; and an operative connection between said controlling element and another of said shiftable gear-units.

5. In a drilling machine, in combination a frame, a spindle feed shaft, automatic means for actuating said feed shaft including par-

allel shafts journaled in said frame, a power shaft, operative connections between said power shaft and one of said parallel shafts, sliding gear units translatable mounted on said parallel shafts for effecting an operative connection between said power shaft and said feed shaft, a controlling element for shifting said gear units having movements in one plane for shifting one of said gear units and in a plane transverse to the first mentioned plane to shift another of said gear units.

6. In a drilling machine in combination a spindle feed shaft, automatic means for actuating said shaft including a power shaft and shiftable gear units, manual means for actuating said feed shaft, means for shifting said gear units to effect an operative connection between said power shaft and said feed shaft and means intermediate said gear shifting means and said manual means and actuated by the former means for rendering said manual means ineffective.

7. In a drilling machine, in combination a spindle feed shaft, manual means for actuating said feed shaft, automatic means for actuating said shaft including a power shaft and shiftable gear units, a single controlling element having movements in transverse directions for shifting said gear units, connections between said controlling element and said gear units for shifting the latter to effect an operative connection between said power shaft and said feed shaft each of said connections being actuated by one only of said transverse movements and means actuated by one of said movements for rendering said manual means inactive.

8. In a drilling machine in combination a spindle feed shaft, manual means for actuating said shaft, automatic means for actuating said shaft including shiftable gear units, a controlling element movable in one plane for shifting one of said gear units and in another plane for shifting another of said gear units, a rotatable sleeve upon which said controlling element is pivoted, a cam surface formed in said sleeve, and means actuated by said cam surface for rendering said manual feed actuating means ineffective.

9. In a drilling machine, in combination a spindle feed shaft, a power shaft, a third shaft, means for driving said third shaft from said power shaft at any one of a predetermined number of speeds said means including a shiftable gear unit, a clutch member secured upon said third shaft, manual means carried by said third shaft for actuating said feed shaft said manual means including a clutch member normally engaging said first mentioned clutch member, controlling means for shifting said gear unit and means actuated by said controlling means for disengaging said clutch members.

10. A feeding mechanism for drilling ma-

chines comprising a power shaft; a spindle feed-shaft; a third shaft; a driving connection between said third shaft and said feed-shaft; a plurality of relatively shiftable gear-units, providing a plurality of feed changes, operatively connecting said third shaft with said power shaft; and means for selectively meshing the gears of said gear-units to effect any one of a plurality of available feeds in 5 said spindle feed shaft, said means comprising a rotatable sleeve provided with a cam-groove; a slide-rod; a fork secured to one end of said slide-rod and engaging one of said gear-units; a roller secured to the opposite 10 site end of said slide-rod and tracking said cam-groove; a yoke pivoted to said sleeve transversely to and at one side of the axis of said sleeve; an extension on said yoke; a second slide-rod provided at one end with a 15 fork engaging another of said gear-units and at its opposite end with a segment engaging said extension; and a hand-grasp on said yoke for turning said yoke about its pivot to shift one gear-unit and for rotating said 20 sleeve to shift another of said gear-units.

11. A drilling machine combining a spindle feed shaft; automatic means for actuating said shaft including a power shaft and shiftable gear-units; manual means for actuating said shaft including a third shaft, operatively connected with said spindle feed shaft; a sleeve keyed to said feed-shaft and provided with clutch teeth; a hand-wheel provided with a hub; a sleeve journaled upon 25 said third shaft and keyed to said hub;

clutch-teeth formed in said last named sleeve; a spring normally acting to hold said two sets of clutch-teeth together; a rotatable sleeve, provided with a gear-shifting cam-groove and two clutch-disengaging cam surfaces, journaled co-axially with said third shaft; an operative connection between said cam-groove and one of said shiftable gear-units; a clutch-disengaging ring intermediate said sleeve and the hub of said hand-wheel and provided with a tooth adapted to engage said two clutch-disengaging cams; and manual means for rotating said sleeve to cause said cam-groove to shift one of said gear-units and simultaneously shift said clutch-disengaging ring against the action of the spring to disengage said clutch-teeth and thereby render said manual feed ineffective.

12. The combination set forth in claim 11 characterized by this, that the rotatable gear-shifting sleeve is also provided with a plurality of detent notches located at opposite sides of said clutch-disengaging cams and adapted to receive the point of said tooth to hold the sleeve against accidental rotation after it has been manually rotated to shift one of said gear-units.

In witness whereof, I hereunto subscribe my name, as attested by the two subscribing witnesses.
